UNITED STATES PATENT OFFICE.

EDWARD J. GRANGER, OF CHICAGO, ILLINOIS, ASSIGNOR TO DAVID S. GARDNER, OF CHICAGO, ILLINOIS.

METHOD OF FORMING FOLDED INSERTS FOR GAME-BOARDS.

1,260,767.

Specification of Letters Patent. Patented Mar. 26, 1918.

Application filed March 26, 1917. Serial No. 157,516.

To all whom it may concern:

Be it known that I, EDWARD J. GRANGER, a citizen of the United States, and a resident of the city of Chicago, in the county of Cook and State of Illinois, have invented certain new and useful Improvements in Methods of Forming Folded Inserts for Game-Boards, and I do hereby declare that the following is a full, clear, and exact description of the same, reference being had to the accompanying drawings, and to the numerals of reference marked thereon, which form a part of this specification.

This invention relates to a method of folding and forming folded inserts such as performed by a machine forming the subject matter of my co-pending application for "folding and plaiting machine," filed of even date herewith, Serial No. 157,515.

This invention relates to a method of forming a plurality of small folded pieces of strips of paper or other material which may have any desired characters imprinted or marked thereon for use in a game board provided with small apertures into which the folded marked strips are inserted so that the characters thereon are entirely concealed. Heretofore it has been the practice to wind small numbered or marked strips of paper into spiral form for insertion into the apertures in the game board, but this has been a tedious operation.

This invention contemplates using long strips of material which are transversely perforated to divide the strips into divisions on which characters are marked, and then folding or plaiting the strip longitudinally so that each of the divisions thereof is plaited transversely throughout its length and the small folded divisions may then be separated along the lines of perforation and readily inserted through the apertures provided therefor in a gameboard.

It is an object therefore of this invention to provide a method of folding small strips of material by first perforating a long strip of the material transversely, and then plaiting or folding the entire strip longitudinally, and thereafter tearing or separating the perforated divisional portions of said strip along the lines of perforation therein while in the folded state.

It is furthermore an important object of this invention to provide an improved method of folding a number of small strips

of material by folding a large sheet or strip of the material, and then separating parts therefrom along lines of perforations provided in the folded material, so that the divisional parts separated therefrom are each 60 in folded condition.

Other and further important objects of my invention will be evident from the disclosure in the drawings and specification.

The invention (in a preferred form) is 65 illustrated in the drawings, and hereinafter more fully described.

On the drawings:

Figure 1 is a plan view of a perforated strip of material prior to folding thereof. 70

Fig. 2 is a plan view of the strip after the same has been longitudinally creased and with the reference characters omitted.

Fig. 3 is a plan view of the strip after the same has been tightly folded along the 75 creases therein.

Fig. 4 is an end view of the strip shown in Fig. 2.

Fig. 5 is an end view of the strip shown in Fig. 3. 80

Fig. 6 is a fragmentary plan view of a game board illustrating the insertion of the small folded divisional parts of the strip into apertures therefor.

As shown on the drawings:

The strip with the characters thereon, is denoted as a whole by the reference numeral 1, and is provided with a plurality of transverse lines of perforations 2. After the strip is longitudinally plaited or creased, thereby slightly reducing the width thereof, it has the appearance shown in Figs. 2 and 4, and denoted as a whole by the reference numeral 3. The creased strip shown in Fig. 2, is then folded tightly into the compressed form shown in Figs. 3 and 5, and denoted as a whole by the reference numeral 4, and the sections or divisions may then be separated therefrom along lines of perforation, one of the separated folded divisional parts being denoted by the reference numeral 5. The game board is denoted as a whole by the reference numeral 6, and is provided with receiving pocket-holes or apertures 7, into which the small folded divisional parts 5, of the numbered strip, are inserted, and a concealing sheet or surface 8, is then pasted or otherwise secured over the game board to conceal the folded inserts therein. Said sheet 8, how- 110

ever, is marked with dotted circles which are registered over the pockets in the game board.

5 In using the game board, a plug, pencil, or other device is registered over one of the dotted circular indications on the surface 8, and thrust therethrough, thereby breaking through the sheet 8, passing into the aperture 7, and thrusting the folded divisional numbered strip 5, outwardly through 10 the back of the game board, and the strip may then be unfolded and examined to ascertain the characters thereon.

I am aware that various details of my invention may be varied through a wide range 15 without departing from the principles thereof, and I therefore do not purpose limiting the patent granted otherwise than necessitated by the prior art.

20 I claim as my invention:

1. A method of providing small folded

strips of material consisting in transversely perforating a long strip of material, longitudinally creasing the same, folding the longitudinal strip transversely and severing the divisional portions from said strip along the transverse lines of perforations.

2. A process of forming a folded insert for game boards comprising transversely perforating a long strip of paper at short 25 distances apart, making longitudinal creases in the strip, pressing the longitudinal folds tightly together and severing the strip at the perforations making small folded portions.

In testimony whereof I have hereunto subscribed my name in the presence of two 30 subscribing witnesses.

EDWARD J. GRANGER.
